KNIFE BAR SHAPING MACHINE

Charles E. Cleveland, Kendallville, Ind.

Application July 20, 1933, Serial No. 681,339

7 Claims. (Cl. 153—32)

This invention relates to improvements in knife-bar shaping machines adapted for imparting spiral formation to straight bars as is required in the construction of such implements as lawn mowers of the reel type, and in some respects has characteristics similar to those disclosed in my previous application for knife-bar shaping machines, Ser. No. 646,275, filed December 8, 1932.

One of the objects of the instant invention is to provide in a machine for bending metallic bars a platen disposed to turn upon an axis in conjunction with a series of traveling rollers by which a metallic bar is made to conform to the platen and cause the required turning movement of the platen as the machine is operated.

A further object is to construct the machine so that in the operation thereof only a small amount of power is required.

Other objects and advantages of the invention will appear in the following description.

An illustrative embodiment of the invention is shown in the accompanying drawings, in which:

Fig. 1 is a side elevation of the machine embodying the invention;

Fig. 2 is a rear end elevation projected from Fig. 1;

Fig. 3 is a top plan view of the machine; and

Fig. 4 is an enlarged fragmentary cross section of Fig. 1 on the line x—x thereof.

The illustrative embodiment of the invention consists of a hollow pedestal 1 upon the top of which are disposed parallel horizontal guideways 2 and a pair of brackets 3 disposed respectively at the opposite ends of the pedestal and to one side thereof. A carriage 4 is mounted on the guideways 2 upon which it has guided sliding movement. The carriage has uprights 5 and 6 in the upper ends of which are disposed two shafts 7 and 8 that extend transversely with respect to the carriage, the one being located in front of the other. The axes of the two shafts 7 and 8 extend respectively in transverse planes that are convergent from the outer ends of the shafts toward the inner ends thereof. Upon the inner end of each of the shafts 7 and 8 are loosely disposed a corresponding pair of blade forming rollers 9—9' and 10—10', each of which has free turning movement upon its complementary supporting shaft.

In the uprights 5 and 6 is also mounted a transverse shaft 11 having loosely disposed upon its inner end a platen supporting roller 12 so as to have free turning movement thereon, the shaft 11 being located at a point below the shafts 7

and 8 a sufficient distance as to afford a substantial space between the blade forming rollers and the platen supporting roller.

In the upright 5 located between the shafts 7 and 11 is provided a slot 13 for the accommodation of the trunnions 14 of a blade confining roller 15, the axis of which preferably intersects the axes of said shafts 7 and 11. The trunnions 14 are loosely confined in said slot so as to permit turning movement of said blade confining roller.

Between the brackets 3 is disposed a platen 16 of spiral formation which is provided at each end with an arm 17 having a complementary trunnion 18 that is supported by and has rotating movement in the corresponding bracket and the platen turns upon the axis thereof. The platen 16 has a radially disposed face 19 exposed upwardly and which extends spirally from one end thereof to the other, and along the inner margin of said face parallel with the outer margin of the platen is an upwardly projecting shoulder 20. The platen 16 extends into the space between the forming rollers 9—9', 10—10' and the supporting roller 12 so that its outer edge bears against the confining roller 15. When the carriage 4 is reciprocated upon the guideways 2 the platen accommodately turns upon the axis of its trunnion 18. The platen is so proportioned that when a blade 21 is inserted on the face 19 beneath the forming rollers and between the shoulder 20 and the confining roller 15, the blade is closely compressed upon the face of the platen and between the shoulder and the confining roller, and is bent into spiral form during its passage beneath the forming rollers 9—10 and 9'—10'. The twisting of the blade is due to the divergence of the axes upon which the forming rollers revolve, the spiral form of the face of the platen, and the pressure of the forming rollers upon the blade as the platen is turned.

A pin 22 on the platen projects upwardly from the face 19 thereon preferably adjacent one end thereof which serves as an anchor for securing the blades in proper position on the platen face when they are fed to the machine, the blades being perforated suitably for the reception of the pin.

The carriage 4 is reciprocated upon its guideways by any suitable driving mechanism. As an example, there is shown in the drawings a drive shaft 23 supported in bearings 24 and provided with a pulley 25 which is connected with a suitable source of power by a belt (not shown). One end of the shaft 23 extends into the pedestal 1 and has secured thereon a crank 26, and a slotted

arm 27 has swinging movement in the pedestal upon a shaft 28 located in the bottom thereof. The upper end of the arm 27 has a sliding block 29 therein that is connected with the carriage 4 by means of a pin 30. The crank 26 is connected at its outer end by a pin 31 with a block 32 that has sliding movement in the slotted arm so that as the crank revolves reciprocating movement is imparted to the carriage through the medium 10 of the swinging arm.

In the operation, while the carriage is at the forward end of its stroke a knife-blade to be shaped is introduced upon the face 19 of the platen with one end secured to the pin 22 so that upon subsequent stroke of the carriage the forming rollers travel over the top face of the blade while the platen travels upon the supporting roller 12 and is thereby sustained so that the blade is compressed between the face 19 on the 15 platen and the forming rollers, and also, is confined laterally between the roller 15 and the shoulder 20 on the platen during the forming travel of the carriage. During this operation the blade is subjected while under pressure imposed 20 upon it by the forming rollers against the face of the platen, a spiral form corresponding to that of the face of the platen.

Generally, the knife-blades in their initial form are so shaped that their outer margins are of 30 less thickness than their back portions, and consequently the forming rollers 9 and 10, and also the forming rollers 9' and 10' are correspondingly made of different diameters. All of the forming rollers are independently revolvable upon their 35 respective shafts and therefore their travel upon the blade is without frictional interference with each other or with the blade although the circumferences of the rollers differ in extent. A feature of the invention is that the platen, and the 40 blade during its formation thereon are held confined between the forming rollers and the supporting roller, while the blade is confined laterally between the roller 15 and the shoulder 20 on the platen. In this manner the blade is forced into 45 the desired spiral shape.

I claim:

1. In a knife-bar shaping machine, a pedestal having guideways and stationary brackets, a platen supported by said brackets to have turning 50 movement about an axis and having a spiral radially disposed face and provided with a shoulder extending parallel with and spaced from the outer edge of said face, a carriage having reciprocating movement on said guideways, two shafts 55 in the upper part of the carriage that extend transversely with respect thereto, one being located in front of the other, and the axes of which extend respectively in transverse planes that converge toward the inner ends of said shafts, blade forming rollers on the inner ends of said shafts that overhang the spiral radial face of said platen, another shaft transversely mounted in said carriage having upon its inner end a supporting roller upon which said platen travels, 60 a blade confining roller mounted in said carriage to turn upon an axis that intersects the axes of the foremost of the first-mentioned shafts and the shaft for the supporting roller, and mechanism operatively associated with the carriage for 65 imparting reciprocating movement thereto.

2. In a knife-bar shaping machine, a pedestal, a spirally shaped platen mounted in connection with the pedestal to have turning movement about an axis and having a radially disposed face, a

shoulder extending along the inner edge of said face, a carriage mounted in connection with the pedestal to have reciprocating movement parallel with the axis for said platen, two shafts mounted transversely in said carriage that extend respectively in transverse planes convergently toward said platen, and having upon their inner ends forming rollers that overhang the radial platen face, a supporting roller disposed in said carriage upon which the spiral platen travels as 80 said carriage is reciprocated, a blade confining roller disposed in said carriage engageable with the outer edge of a blade positioned on said platen between its spiral face and said forming rollers, and mechanism for reciprocating said carriage. 85

3. In a knife-bar shaping machine, a spirally shaped platen mounted to have turning movement upon an axis and having a radially disposed forming face and shoulder extending along the inner edge of said face, forming rollers spaced apart disposed to turn upon relatively divergent axes that extend transversely respecting the axis for the platen and that overhang said face, a supporting roller upon which said platen travels, a blade-confining roller disposed adjacent the 100 platen opposite the shoulder thereon, and mechanism to impart relative travel of said rollers longitudinally with respect to the platen. 90

4. In a knife-bar shaping machine, a spiral platen mounted to turn upon an axis and having 105 a radial forming face and a shoulder extending along the inner edge of said face, a supporting roller upon which said platen travels, forming rollers spaced apart and disposed to turn upon axes that extend transversely respecting the axis 110 of said platen, said platen and rollers being arranged so that the platen is confined between the supporting roller and the forming rollers, a blade confining a roller adjacent the platen opposite the shoulder thereon, and mechanism to impart 115 relative travel of said rollers longitudinally with respect to the platen.

5. In a knife-bar shaping machine, a spiral platen mounted to turn upon an axis and having a radial forming face and a shoulder extending 120 along the inner edge of said face, a supporting roller upon which said platen travels, forming rollers spaced apart and disposed to turn upon axes that extend transversely respecting the axis 125 of said platen, said platen and rollers being arranged so that the platen is confined between the supporting roller and the forming rollers, and mechanism to impart relative travel of said rollers longitudinally with respect to the platen. 130

6. A knife-bar shaping machine having a spiral platen mounted to have turning movement upon an axis, a supporting roller upon which said platen travels, forming rollers disposed upon relatively divergent axes and located opposite said supporting roller respecting said platen, a blade 135 confining roller adjacent the outer edge of the platen, and mechanism to impart relative travel of said rollers longitudinally with respect to said platen. 140

7. A knife-bar shaping machine having a spiral platen mounted to have turning movement upon an axis, a supporting roller upon which said platen travels, forming rollers disposed upon relatively divergent axes and located opposite said supporting roller respecting said platen, and mechanism to impart relative travel of said rollers longitudinally with respect to said platen. 145
